UNITED STATES PATENT OFFICE.

STEPHEN E. JACKMAN, OF BROOKLYN, NEW YORK.

CAR.

SPECIFICATION forming part of Letters Patent No. 737,410, dated August 25, 1903.

Application filed September 27, 1902. Serial No. 125,092. (No model.)

To all whom it may concern:

Be it known that I, STEPHEN E. JACKMAN, a citizen of the United States, and a resident of the city of New York, (Coney Island, borough of Brooklyn,) in the county of Kings and State of New York, have invented a new and Improved Car, of which the following is a full, clear, and exact description.

The invention relates to amusement devices, such as inclined or switchback railways, of the kind shown and described, for instance, in the application for Letters of the United States filed by me under even date herewith, Serial No. 125,091.

The object of the improvement is to provide a new and improved car arranged for convenient and safe coupling to another car and having a brake mechanism under the control of the attendant to permit of checking the speed of the car on the downslope, the car also having a circuit-closer for closing a circuit in the track to annunciate the position of the car on the track.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a side elevation of the improvement. Fig. 2 is a longitudinal sectional elevation of the same. Fig. 3 is a rear end view of the same, the track being shown in section. Fig. 4 is a plan view of the car-truck, part being in section. Fig. 5 is a transverse section of the same on the line 5-5 of Fig. 4. Fig. 6 is a side elevation of the coupling for coupling adjacent cars together. Fig. 7 is a plan view of the same. Fig. 8 is a longitudinal sectional elevation on the line 8-8 of Fig. 4 of the fork and its casing for engagement by the elevating-chain. Fig. 9 is an enlarged transverse section of one of the car-wheels and its mounting; and Fig. 10 is a cross-section of part of the brake, showing the electric circuit-closer of the car in position for closing the circuit.

The car-body A is mounted in a suitable manner on a car-truck B, on the sides of

which are secured brackets C, each carrying in its top portion a vertically-disposed pivot D, (see Fig. 9,) on the lower end of which is 55 journaled the middle portion of a fork E, supporting in its sides an axle F, engaging the hub G' of a car-wheel G, mounted to travel on the track-rail H of the continuous track, as plainly indicated in Figs. 1, 2, and 3. 60

The forks E of the front car-wheels are pivotally connected with each other by a cross-bar E', and a similar cross-bar E' connects the forks E of the rear car-wheels with each other, as plainly indicated in Fig. 4. 65

By the arrangement described the car-wheels G are free to revolve on their shafts, secured by set-screws F' in the forks E, and the forks are free to turn on the vertical pivots D; but the forks of the front wheels and 70 those of the rear wheels turn in unison with each other, owing to the pivotal connection by the cross-bar E', which insures proper turning of the car around curves without undue friction or binding of the car-wheels on the 75 track-rails.

In the top of each bracket C is formed an oil-well C', containing an oil or other suitable liquid lubricant, and the bottom of this oil-well C' is connected by a block C² of a porous 80 material—such as ratan, porous oak, or the like—to connect the oil-well with an opening E² in a bearing-plate E³, resting on a bearing-plate E⁴, having an annular groove E⁵ in register with the opening E², the said bearing- 85 plates E³ and E⁴ being interposed between the top of the fork E and the under side of the top portion of the bracket C, as plainly indicated in Fig. 9, to allow convenient turning of the fork E on the pivot D. Now the lubricant percolating through the oil-block C² to the opening E² passes into the annular groove E⁵ and between the bearing-plates E³ and E⁴, so as to thoroughly and continually lubricate the same. An annular oil-well G² 90 is formed in the web of each car-wheel G around the hub G', and a block G³, similar to the block C², is held in the hub G' to connect the oil-well G² with the axle F to lubricate the same. A channel F² is formed in the axle F and leads from one outer end of the same to the middle portion thereof to allow of lubricating the axle by the operator whenever it is deemed necessary to do so. 95 100

In the top of each bracket C and near the outer end thereof is arranged a horizontally-disposed friction-wheel I, mounted to rotate loosely on a suitable spindle I', screwed in 5 the bracket C and secured therein by a set-screw I², as plainly shown in Fig. 9. The friction-wheels I are adapted to travel on side guard-rails H', forming part of the track, as plainly shown in Fig. 3. The tops of the 10 brackets C on each side of the car are connected with each other by guard-plates J, extending immediately below a horizontal guard-rail H², likewise held on the track to prevent a car from jumping up off the car- 15 wheels G to leave the rails H, as will be readily understood by reference to Fig. 3. The plates J also serve as a step for passengers stepping into or out of the cars.

Directly above each guard-plate J is arranged 20 a longitudinally-extending rubbing-plate J' for engagement by the free ends of safety-catches arranged in the up-track of the inclined railway, as more fully shown and described in the application above referred 25 to. On the front end of the car are arranged guard-plates J², in alignment with the rubbing-plates J', to prevent the car from being injured by the said safety-catches when the car travels up the inclined railway.

In order to enable the attendant to keep 30 control of the speed of the car, I provide a suitable brake mechanism, consisting, essentially, of longitudinal brake-shoes K, one on each side of the car, adapted to engage brake- 35 rails H³, arranged in the track inside of the track-rails H, as illustrated in Fig. 3. The brake-shoes K are hung on depending arms K', K², and K³, of which the arms K² and K³ of each brake-shoe have their pivots K⁴ journaled in suitable bearings carried on the truck D, while the arms K' of the two brake-shoes are secured on a single pivot K⁵, extending transversely on the truck and journaled in suitable bearings thereon. On this 40 pivot K⁵ is secured an upwardly-extending lever K⁶ within convenient reach of the attendant of the car, so as to enable the same to impart a turning motion to the pivot K⁵ to swing the arms K' and the brake-shoes K 45 downward in engagement with the brake-rails H³ to brake the car, it being understood that the arms K² and K³ of each brake-shoe serve to insure a parallel swinging movement of the brake-shoes to properly engage the 50 same throughout their length with the brake-rails H³. A very powerful brake mechanism is thus provided.

Brake-shoes L and L' for the front and rear 55 wheels of the cars are also provided and hung on transverse shafts L² and L³, journaled in suitable bearings in the truck D, and on the said shafts are arranged upwardly-extending arms L⁴ and L⁵, connected with each other by links L⁶, made in sections, with turnbuckles 60 L' to allow of adjusting the position of the shafts L² and L³ relative one to the other to bring the brake-shoes L and L' in proper re-

lation to the front and rear car-wheels. On the front shaft L² is secured a depending arm L⁸, connected by a link L⁹ with an arm L¹⁰, mounted to turn loosely on the pivot K⁵, previously referred to, and the said arm L¹⁰ is provided with an upwardly and forwardly extending foot-piece L¹¹, adapted to be engaged by the foot of the attendant to turn the arm L¹⁰ on the pivot K⁵ to turn the shafts L² and L³ to bring the brake-shoes L and L' in braking contact with the car-wheels G. When the operator releases the pressure on the foot-piece L¹¹, the brake-shoes L and L' swing off the wheels by their own weight.

On the under side of the car is arranged a fork N, adapted to be engaged at its free ends by cross-bars of the elevating-chain used for drawing the car up the incline, and the said fork N is hung loosely on a pivot N', arranged in a casing N², secured to the truck B, the said casing being open at its bottom and arranged in such a manner that the fork N can swing upwardly and rearwardly to 85 pass over obstructions in the track, but is prevented from swinging forwardly by abutting against the vertical front wall N³ of the casing N², as plainly indicated in Fig. 8.

In order to allow of coupling several cars together to form a train, I provide each car with a longitudinally-extending draw-bar O, fulcrumed at O' on the truck-frame and extending over a guide-plate B' beyond the end of the car, as plainly indicated in Figs. 6 and 7. The outward end of the draw-bar is connected by a transverse pivot O² with a coupling-link O³, having a lug or projection O⁴ at each end adapted to swing in engagement with the top of the draw-bar O to prevent coupled cars from jumping upward off the track-rails. On the end of each car and directly over the draw-bar O is arranged a bracket O⁵ to prevent the projecting end of a draw-bar from being bent on an unusual strain.

In order to enable the operator in charge of the inclined railway to determine at what point a car is traveling at the time, I provide in the track a number of circuits connected with alarms or annunciations, each circuit being normally opened and closed by a wheel P, carried at the rear of the car, so that when this car passes over the circuit in the track the said circuit is closed and the corresponding alarm or annunciation is given at the station. The wheel P on the car has a metallic rim and is journaled in a suitable bearing P', mounted to slide vertically in suitable bearings on the car, the bearing being 125 pressed by a spring P² to normally hold the bearing and its wheel in lowermost position to engage contact-plates Q and Q', held insulated on the top of blocks Q² and Q³, arranged in the track, as plainly indicated in Figs. 1 130 and 10. The ends of the blocks Q² and Q³ are beveled to allow the wheel P to easily travel up the same against the tension of the spring P² of its bearing P' to connect the

contact-plates Q and Q' with each other, thus closing the circuit. The contact-plates Q and Q' are provided with suitable binding-posts Q⁴ and Q⁵, from which lead positive and negative wires R and R' to the annunciator or alarm of any approved construction located in the station.

Having thus described my invention, I claim as new and desire to secure by Letters Patent—

1. A car having longitudinal brake-shoes for engagement with fixed brake-rails in the track near the sides thereof, arms on which the shoes are hung, transverse pivots journaled on the car and carrying the arms, one of the pivots extending across the car and carrying the arms of both shoes, and a hand-lever on this pivot, under the control of the operator, as set forth.
2. A car having brake-shoes for engagement with fixed brake-rails; means for holding said shoes in operative relation to said rails; a hand-lever adjacent the seat of the rider for applying said brakes to said rails; brakes for the wheels of the car; and a foot-lever adjacent the seat of the rider for operating said brakes; said hand-lever being adapted to be pulled backwardly to operate its brakes, and said foot-lever being adapted

to be moved forwardly to apply the wheel-brakes, whereby each lever forms a point of purchase or of bracing for the rider when operating the other lever; and a part of the power thus exerted upon either lever reacts upon the other.

35

3. A car having a car-wheel, a fork, in the sides of which the wheel is journaled, a pivot engaging the middle portion of the fork, a bracket on the car, in which the pivot is journaled, and a bearing between the bracket and the middle portion of the fork, said bracket containing an oil-reservoir in communication with said bearing as set forth.

40

4. A car having side brackets to which the car-wheels are journaled, and longitudinal plates on the said brackets, projecting horizontally from the sides of the car to engage the under side of car-rails in the sides of the car-track, to prevent the car from leaving the track, as set forth.

45

In testimony whereof I have signed my name to this specification in the presence of two subscribing witnesses.
